UNITED STATES PATENT OFFICE.

WILLIAM S. RICHARDSON, OF BOSTON, MASSACHUSETTS, ASSIGNOR TO THE BALL AND SOCKET FASTENER COMPANY, OF SAME PLACE AND NASHUA, NEW HAMPSHIRE.

DESIGN FOR A SOCKET MEMBER FOR FASTENERS.

SPECIFICATION forming part of Design No. 30,315, dated March 7, 1899.

Application filed November 25, 1896. Serial No. 613,461. Term of patent 14 years.

To all whom it may concern:

Be it known that I, WILLIAM S. RICHARDSON, a citizen of the United States, residing at Boston, in the county of Suffolk and State of Massachusetts, have invented a new and original Design for the Socket Member of a Fastener for Gloves and other Articles, of which the following is a full, clear, and exact description, reference being had to the accompanying drawings, forming a part of this specification, in explaining its nature.

The design relates to a portion of the socket member of a fastener for gloves and other articles; and it comprises a cylindrical section or barrel having a contracted opening at one end and also having at the other end an outwardly-turned curved flange in which there is formed radiating depressions which extend from the opening to the outer edge and which produces a curved oval figure with downwardly-inclined sides.

In the drawings, Figure 1 is a perspective of the section of the fastener, and Fig. 2 is a

plan view thereof. Fig. 3 is a vertical section thereof.

²⁵ *a* is the part as a whole. It has a central opening or cavity *a'*, surrounded by a cylindrical wall, the inner or lower edge of which is contracted. From the outer end of the wall there extends an outwardly-bowed annular ³⁰ section or flange *a²*, rounded upward from its inner edge to its outer edge, and it has extending across it from its inner edge to its outer edge radiating depressions which have inclined sides and produce an oval effect in ³⁵ plan.

Having thus fully described my invention, I claim and desire to secure by Letters Patent of the United States—

The design for a socket member of a fastener as herein shown and described.

WILLIAM S. RICHARDSON.
